UNITED STATES PATENT OFFICE.

HARLOW H. WOODHAM, OF SANTA MONICA, CALIFORNIA, ASSIGNOR OF ONE-HALF
TO ALICE E. WOODHAM, OF LOS ANGELES, CALIFORNIA.

MOVABLE DOOR STRIP.

Application filed May 31, 1928. Serial No. 281,910.

This invention relates to closures, and more especially to a strip for automatically closing the space between a closure and its casing.

5 An object of my invention is the provision of a device adapted to be interposed between a closure and its casing, to prevent the passage of air currents therebetween.

Another object is the provision of a device of the character described, useful in sealing a room against the passage of gas or dust-laden currents thereto or therefrom.

One of the specific objects of the invention is to provide a sealing strip automatically operable by the door in closing, to stop the space between the door and its casing.

A further object is the provision of a sealing strip of the general character described, which is adapted to be concealed from view 20 within a groove in that edge of the closure adjacent which it is to be mounted.

The invention possesses other objects and features of advantage, some of which, with the foregoing, will be set forth in the following description of the preferred form of the invention which is illustrated in the drawings accompanying and forming part of the specification. It is to be understood that I do not limit myself to the showing 25 made by the said drawings and description, as I may adopt variations of the preferred form within the scope of my invention as set forth in the claim.

Referring to the drawings:

35 Figure 1 is an elevation of the lower portion of a door and its associated casing, portions of which are broken away to disclose the operative parts of my automatic sealing strip, which are shown in the position occupied thereby when the door is closed and the sealing strip is extended to sealing position.

40 Fig. 2 is a vertical sectional view, the plane of section being indicated by the line 2-2 of Fig. 1.

45 Fig. 3 is an elevation of the door of Fig. 1, with a portion thereof broken away to disclose the operative parts of my sealing strip in the position assumed thereby when the door is opened and the sealing strip moved away from sealing position.

50 Fig. 4 is a vertical sectional view, the plane of section being indicated by the line 4-4 of Fig. 3.

55 Fig. 5 is an elevation of the other side of

the door of Fig. 1, with a portion thereof broken away to disclose the sealing strip in the same position as in Fig. 1.

Fig. 6 is a perspective view of a portion of the sealing strip alone, showing the position thereof in respect to the door casing, which it would occupy were it mounted in the associated door.

Fig. 7 is a perspective view of a portion of the anchoring plate.

Fig. 8 is a perspective view of a portion of the driving strip.

Broadly, the device of my invention comprises a device for closing the space between a door and its casing. The device is 70 adapted to be so mounted adjacent the edge of the door that it is automatically moved by the door in closing, to an extended position wherein it effectually closes whatever space may be left between the edge of the 75 door and the casing. Means are provided for retracting the strip when the door is opened, to permit free movement of the door.

I am aware that my invention is adaptable to a variety of closures and for a variety of purposes. For example, it may be used in conjunction with a door, window or lid of either the swinging or sliding type. The invention may be used to prevent 85 drafts, to prevent rain from flowing between a closure and its casing, or to seal off a room or compartment to prevent the flow of gas or dust into or out of the room past its normal closure.

90 Specifically describing the present embodiment of my invention, it is shown mounted within a groove 6 within the bottom edge 7 of a door 8. All of the operative parts of my improved sealing device are receivable within the groove 6 or upon the bottom edge 7 of the door, with the result that the entire device is concealed from view and detracts in no manner from the normal appearance of the door.

100 An anchoring plate 11 is provided as a support for the other portions of the device. The anchoring plate 11 corresponds substantially in length to the length of that edge of the door to which the sealing device is to be applied, in the present instance, to the length of the lower edge 7 or width of the door 8. Means for attaching the anchoring plate in position are provided in the form of a flange 12 extending laterally 105 110

from the bottom edge of the plate 11 and adapted to extend under a portion of the lower edge 7 of the door, as clearly shown in Figs. 2 and 4.

5 Any suitable fastening means such as screws 13 may be extended through apertures 14 in the flange 12 to attach the anchoring plate 11 in position. A vertical plate 16 is carried at each end of the anchoring plate 11 to close the associated end of the groove 6; and screws 17 or their equivalent may be driven through apertures 18 in the plates 16 into the door 8, to securely hold them in position.

15 A plurality of slots 19 extend longitudinally of the anchoring plate 11 preferably adjacent the upper edge thereof; and a plurality of transversely extending slots 21 are also provided in the anchoring plate

20 11. A sealing strip 22 is slidably mounted upon the anchoring plate 11, and preferably corresponds thereto in length. In its preferred form, the sealing strip 22 comprises 25 a rigid back 23 with a flexible apron 24 depending therefrom. This apron 24 may be made of felt, rubber or any other suitable material adapted to engage the sill 26 or adjacent part of the casing 27 for the door 30 8, and establish a substantially draft-tight seal therewith. The movement of the sealing strip 22 in respect to the anchoring plate 11 is limited to movement transversely of the anchoring plate 11; or, since in the present 35 instance the anchoring plate is positioned to extend along the bottom edge of the door, the movement of the sealing strip is limited to vertical movement. This is effected by means of a pin 28 extending 40 through each of the vertical slots 21 in the anchoring plate 11 and rigidly attached to the sealing strip 22.

45 A driving strip 31 is slidably mounted upon the anchoring plate 11 and preferably 50 upon the side thereof opposite the sealing strip 22. This driving strip is limited to movement longitudinally of the anchoring plate 11; or, in other words, to horizontal movement, by means of a pin 32 slideable in each of the longitudinally extending grooves 19 and rigidly secured to the driving strip 31. A head 33 is provided on that end of each of the pins 32 on the opposite side of the anchoring plate 11 from the driving 55 strip 31, with the result that they serve to hold the driving strip closely adjacent the anchoring plate 11, as well as to limit the movement thereof to horizontal movement.

An oblique slot 36 is provided in the driving 60 strip 31 in register with each of the vertical slots 21 in the anchoring plate 11. Accordingly, the pins 28 which extend from the sealing strip 22 through the slots 21, may also extend through the inclined slots 36 in 65 the driving strip 31. A head 37 is provided

on that end of each of the pins 28 upon the opposite side of the driving strip 31 from the anchoring plate 11 and sealing strip 22, with the result that the pins 28 serve also to retain the sealing strip 22 closely adjacent the anchoring plate 11.

The inclined slots 36 slope downwards toward that edge of the door 8 upon which the hinges 39 are secured; and as a result of the engagement of the pins 28 therein, when the driving strip 31 is moved away from the hinged edge 38, the pins 28 will be forced vertically downwards within the slots 21, carrying with them the sealing strip 22.

Means are provided for moving the driving strip 31 away from the hinged edge 38 automatically when the door 8 is moved to closing position. A lug 41 is rigidly affixed to the driving strip 31 adjacent the hinged edge 38 of the door, to provide an enlarged shoulder 42 in register with an aperture 43 in the adjacent groove closing plate 16. A plate 46 is positioned to that portion 47 of the casing 27 adjacent the hinged edge 38 of the door 8; and a pin 48 threaded thereto in register with the aperture 43 in the plate 16. A lock nut 49 is threaded upon the pin 48, preferably upon the inside of the plate 46.

The proportionate size and arrangement 95 of the parts is such that as the door 8 moves to closing position, the pin 48 is projected through the aperture 43 to engage the shoulder 42 upon the lug 41 and push the driving strip 31 longitudinally of the anchoring plate 11 away from the hinged edge 38, resulting in the lowering of the sealing strip 22 as previously described. A spring 51 is under tension between a pin 52 rigid with the anchoring plate, and a pin 53 rigid 100 with the driving strip 31, so that as the door 8 moves away from closing position with the subsequent withdrawal of the pin 48 from engagement with the lug 41, the spring 51 returns the driving strip 31 to 105 normal position, and with it, retracts the sealing strip.

Thus it may be seen that I have provided an efficiently operating device for closing the space between a closure and its casing, 115 which is adapted to be automatically moved to sealing position by the closure in closing, and which is adapted to be automatically retracted as the door opens, to permit freedom of movement of the door.

Proper engagement of the sealing strip 22 with the sill 26 or other associated portion of the casing 27 may be effected by adjusting the pin 48 within its supporting plate 46; it being understood that the farther the pin 48 projects from its associated portion of the casing 27, the lower the sealing strip 22 will be forced when the door 8 closes.

I claim:

A device for closing the space between a 130

- closure and its casing, comprising an anchoring plate receivable within a groove in an edge of said closure, a flange extending from the outer edge of said plate and securable to said grooved edge of the closure to rigidly dispose the anchoring plate within the groove and spaced from both sides thereof, a sealing strip slidable transversely of said anchoring plate upon one side thereof, 5 a driving strip slidable longitudinally of said anchoring plate upon the other side thereof, a pin rigid with said sealing strip and extending through a transverse slot in the anchoring plate and through an oblique slot in the driving strip, a pin rigid with 15 said driving strip and extending through a longitudinal slot in the anchoring plate, said pin having a head bearing against the opposite side of the plate from the driving strip, and means operable by the door in closing 20 for moving said driving strip longitudinally.
- 10 In testimony whereof I have signed my name to this specification.

H. H. WOODHAM.
